UNITED STATES PATENT OFFICE.

JACOB ALBERT, OF BALTIMORE, MARYLAND.

COMBINED BUTTON AND LOOP FOR TRACES.

Specification forming part of Letters Patent No. 58,195, dated September 25, 1866.

To all whom it may concern:

Be it known that I, JACOB ALBERT, of Baltimore, in the county of Baltimore and State of Maryland, have invented a certain new and Improved Combined Button and Loop for Fastening Harness-Traces; and I hereby declare the following to be a full, clear, and exact description of the same, reference being had to the accompanying drawings, in which—

Figure 1 represents, in perspective, the combined button and loop when unattached to the trace. Fig. 2 is a transverse vertical section of a whiffletree to which the trace is secured in accordance with my invention, and Fig. 3 is a perspective view of the same.

Harness-traces are ordinarily secured to the whiffletrees of a carriage or wagon by means of small studs or projections on the ends of the whiffletrees, to which the traces are respectively fastened by means of corresponding longitudinal slots or holes punched in their ends, into and through which the said studs or buttons are inserted.

In other traces, called "loop-traces," used in drawing heavy wagons, a device shaped like a buckle without the tongue is secured to that end of the trace which is fastened on the whiffletree. The forward end of the trace is drawn through this buckle, thus forming a running loop, which is placed on the whiffletree in an annular recess or groove turned or formed for its reception. Under this arrangement the tension of the trace will contract the loop and tighten its hold on the whiffletree.

My invention consists in constructing a device, by the employment of which the ordinary trace first above mentioned, may be used either with the button-tree or loop-tree, as occasion may require.

The device consists of a loop of suitable size, having beveled edges and curved shank, terminating in a button or other similar holding device, the whole being formed in one piece.

When it is required to use the ordinary button-trace, which, as above said, has a slot or hole punched in its end as a loop-trace, the combined loop and button invented by me is applied to the trace in the following manner: The punched end of the trace is first inserted through the loop, care being taken to insert it so that the concave surface of the curved shank

shall, when the trace is placed on the whiffletree, be contiguous to the tree. When the trace has been drawn through the loop a sufficient distance, the punched end is bent around, so that the button on the lower end of the device can be inserted through the hole or slot in the trace.

By means of my device a loop is thus formed which, when put on the end of the whiffletree, above described, will serve every purpose for which the common loop-trace is employed.

It will be seen, therefore, that by the employment of my invention, ordinary punched traces can be used indifferently as button-traces or loop-traces, thus rendering it unnecessary to have different sets of traces for the different whiffletrees.

To enable others to understand and use my invention, I will now proceed to describe it by reference to the accompanying drawings.

The device is shown in perspective in Fig. 1.

It consists of a piece of metal or other suitable material. The upper part of this piece is formed into a loop, A, of suitable size and shape, the edges *a a* of which are beveled, as shown more clearly in Fig. 2. The lower end of the piece is shaped so as to form a button, B, which, when inserted through the slot or button-hole *d*, in the end of the trace D, holds that end firmly to the whiffletree E. This button B and loop A are connected by the shank C, whose curved shape is shown more clearly in Fig. 2.

When it is desired to use the ordinary trace as a loop-trace, the change is effected as follows: The punched end of the trace D is inserted through the loop A, the device being held so that the concave surface of the shank shall be turned toward the interior of the loop about to be formed. After the end has been drawn sufficiently through the loop A, it is bent downward until the slot *d* meets the button D. The button is then inserted through the hole *d*, its wings *b b*, after being so inserted, being transverse to the length of the hole. A running loop is thus formed which, when slipped over the end of the whiffletree E into the annular groove or recess *e* formed for its reception, as shown in Figs. 2 and 3, will hold the trace firmly to the tree. The tension of the trace will cause the loop to bind the tree

tightly, the beveled edges *a* of the metal loop and the curve of the shank *C* aiding materially in this respect. When the trace is to be again used with the button-whiffletree, the device can be removed by disengaging the button *B* from the slot *d*, and then drawing back the trace through the loop *A*.

Having fully described my invention, what I claim, and desire to secure by Letters Patent, is—

The herein-described device, whereby the ordinary harness-trace can be used with whif-

fletrees of different construction, as described, the same consisting of a beveled loop, curved shank and button formed in one piece, under the arrangement and for operation substantially as herein set forth.

In testimony whereof I have signed my name to this specification before two subscribing witnesses.

JACOB ALBERT.
